UNITED STATES PATENT OFFICE.

ELMER E. PERKINS, OF CHICAGO, ILLINOIS.

DRYING-ROOM.

1,164,391.

Specification of Letters Patent. Patented Dec. 14, 1915.

Application filed February 27, 1915. Serial No. 10,890.

To all whom it may concern:

Be it known that I, ELMER E. PERKINS, a citizen of the United States, residing at Chicago, in the county of Cook and State of Illinois, have invented certain new and useful Improvements in Drying-Rooms, of which the following is a specification.

This invention relates to drying rooms for drying lumber, veneers, furniture and various other wooden articles, and has more particular reference to drying rooms of the inclosed type commonly known as condensing rooms or kilns in which the air is alternately heated and circulated around the articles to be dried and then cooled to condense the moisture which it has absorbed from the articles, whereupon the air is again heated and circulated. Drying kilns of this general character, as heretofore constructed, have comprised cooling coils located at one side of the kiln and separated from the drying room proper by a vertical partition, and heating coils positioned near the bottom of the room beneath the material or articles to be dried. The air cooled by the condensing coils flowed downwardly along one side of the kiln beneath the cooling coils to the floor and thence along the floor until it rose past the heating coils by reason of the distributing action of the coils. In kilns of this character some means was invariably provided beneath the heating coils to distribute the air to the coils. The distributing means employed varied in different kilns, in some instances consisting of a floor beneath the coils having openings arranged in spaced relation through which the air would rise to the coils. In other kilns a distributing diaphragm or wall was employed so that part of the cooler air would be forced to flow beneath the diaphragm to the opposite side of the kiln from the cooling coils before the air would be permitted to rise to the heating coils. These various distributing devices beneath the heating coils together with the vertical partition, between the cooling coils and the drying room proper not only complicated the construction of the kiln and increased its initial cost of installation but also added to the danger of fire, and in accordance with the underwriters' requirements, kilns so constructed must be equipped with sprinkler heads beneath the coils.

One of the primary objects of my present invention is to construct a kiln or drying

room of the general character indicated, which will be entirely free from vertical partitions and horizontal floors, diaphragms or other air-distributing means beneath the heating coils.

Another object of my invention is to provide a kiln which will be extremely simple in construction and which can be installed at a minimum cost and at the same time will be more effective and efficient in operation than the complicated constructions heretofore employed.

A further object of my invention is to effect a thorough distribution of the air in the kiln and to provide for the required circulation by an arrangement of the heating and cooling devices themselves without the aid or necessity of deflectors, fans or other auxiliary distributing and circulating devices.

Other objects and many of the inherent advantages of this invention will be readily appreciated as the same becomes better understood by reference to the following description when considered in connection with the accompanying drawings.

Referring to the drawings—Figure 1 shows a perspective view of a drying room embodying one form of my invention, and Fig. 2 is a similar view of a room embodying a slightly modified form of my invention.

On the drawings reference characters 3 and 4 indicate the side walls of my drying room and 5 and 6 the floor and ceiling respectively of the room, all of the walls being preferably constructed to provide suitable dead air spaces so that the room will be adequately heat-insulated, so as to prevent dissipation and loss of heat from the interior of the room.

A plurality of tracks 7, preferably three in number for each room, are supported usually about two and one-half feet above the floor 5 upon suitable supporting columns 8, these tracks being adapted to support the lumber or other material to be dried which may be piled directly upon the tracks, or, as is usually done, it may be trundled into the room upon trucks or car-bunks constructed to run on these tracks.

Upon the columns 8 beneath the tracks are securely mounted a series of transversely extending channel-bars 9 which serve as supports or hangers for the pipes, which will be later described. Upon one of the vertical side walls, and in the present instance upon

the wall 4, I have mounted, by means of suitable brackets 11, a cooling device 12 in the form of a series of coils of pipes extending longitudinally of the kiln and disposed at varying distances from the wall so that the descending air will be brought into contact with the pipes in its downward travel and be cooled thereby to relieve it of its moisture which is collected in a trough 13 beneath the device and delivered thereby outside the room. Water, brine or any suitable cooling agent is circulated through the coil 12 and the temperature may be controlled by hand regulated or thermostatically-operated valves (not shown). The air cooled by the coil 12 flows directly downwardly along the wall 4 to the bottom of the room where it travels along the floor until it is distributed upwardly throughout the room by heating and distributing means, which will now be described.

Upon the hangers or cross-bars 9 I have mounted a series of longitudinally extending pipes 14 connected together at one end of the kiln by a header 15 and at the opposite end by a header 16. Steam is admitted to the header 15 through a pipe 17 at one side of the kiln and is discharged, preferably at the opposite corner of the room, through a pipe 18 connected with the header 16. It will be observed from Fig. 1 that the first pipe at the left of the room is spaced from the wall 4 about two feet to permit the down-flow of air from the coil. The pipes 14 are spaced apart across the room in continually decreasing spaced relation, as shown in Fig. 1, so that the greatest heat, and consequently, the greatest distributing force, will be generated at the side of the kiln most remote from the wall 4, and the heat and distributing force will be applied in gradually decreasing proportions across the kiln toward the wall 4 with the result that the air cooled by the coil 12 and delivered below the heating pipes will rise uniformly between the pipes and be distributed upwardly throughout the room. If all of the pipes were spaced a uniform distance apart it will be manifest that the cool air from the floor would be drawn upwardly and distributed more rapidly near the wall 4 than it would near the wall 3, since the cooler air would probably not be drawn along the floor 5 entirely across the room to the opposite side from the coil 12. By spacing the pipes varying distances apart, however, so that the greatest force is exerted at the point most remote from the wall 4 where the cooler air enters beneath the pipes I am enabled to produce a uniform distribution of the air throughout the room which will dry the product or articles therein evenly and uniformly in all parts. To insure that the air will be drawn beneath the pipes clear across the floor 5 to the wall 3 I prefer to provide

adjacent to the wall 3 a cluster of pipes 19 arranged outside the right-hand track 7 which distributes air upwardly adjacent to the wall 3.

When the steam is turned on through the pipe 17 the pipes 14 near the wall 3 will first heat up and start the circulation and distribution of the air and as the heat is conveyed to all of the pipes 14 the circulation and distribution will become uniformly effective throughout the entire area of the room, the heated air rising from the pipes 14 around the material or articles to be dried, then flowing along the ceiling 6 toward the cooling coil 12 by which it will be cooled and the moisture will be removed therefrom whereupon the cooled air will drop to the floor 5 and be drawn along the floor and distributed upwardly again by the heating pipes. A uniform circulation and distribution of air in the room is therefore maintained by this construction without the employment of any partitions, false floors, deflectors or other auxiliary distributing devices, and the inside of the room is unobstructed and free to receive the material or articles to be dried. The material itself, which is piled or arranged in the room, prevents any harmful radiation directly from the pipes or cooling coils.

In Fig. 2 I have illustrated a modified form of the invention in that two sets of cooling coils 12 are employed, one on each side of the room, as shown. The heating pipes 14 instead of being arranged in gradually decreasing spaced relation from one side of the room to the other, are disposed in gradually decreasing spaced relation from the sides toward the center of the room. The side pipes are both spaced from the walls 3 and 4, respectively, a sufficient distance to permit down-flow of air from the coils 12 to the floor and the greatest distributing force is exerted along the center of the kiln toward which the air is drawn from both sides and distributed upwardly throughout the room. In this construction a double circulation is effected since the cooling coils on opposite sides of the room will cause two down-currents of cooled air, and the warmer air rising in the room will necessarily flow in both directions along the ceiling to the respective cooling coils. The variable spacing of the heating and distributing pipes, however, insures a thorough distribution of the air throughout the rooms. This form of the invention is particularly efficient when unusually large amounts of moisture are to be removed, but for ordinary conditions the construction shown in Fig. 1 is preferable.

In actual practice the room is equipped with the usual hygrometers and thermometers and, if preferred, the supply of steam to the heating pipes may be thermostatically controlled so as to maintain a predetermined

uniform temperature in the room. The construction, application and operation of these instruments are well known and it is believed that illustration and detailed explanation thereof is unnecessary in this case.

From the foregoing it should be understood that I have provided a drying room which is extremely simple in construction so that it can be economically installed and 10 since all partitions, diaphragms, false floors, deflectors and the like are entirely eliminated, the dangers arising from fire are greatly reduced and the installation of sprinkler heads beneath the heating pipes 15 may be dispensed with. The circulation and distribution of the air in the room is maintained solely by the arrangement of the heating and cooling pipes with the result that the maximum efficiency is obtained with a 20 construction of extreme simplicity. It will be manifest, however, that the details of construction disclosed may be varied within considerable limits without departing from the 25 essence of the invention as set forth in the following claims:

I claim:

1. A drying room comprising a closed drying chamber having means therein for creating and maintaining a complete circuit 30 of air circulation, said means including a heating device arranged and distributed over the floor and spaced from a side wall of the chamber and disposed a short distance above the floor of the chamber but in direct communication with the floor area therebeneath so as to distribute the air directly upwardly through the chamber, and a cooling device 35 within the drying space located directly above the space between the side wall and said heating device with its cooling surface in direct contact with the air of the drying space.

2. A drying room comprising a closed partitionless drying chamber having means for creating and maintaining a complete circuit 45 of air circulation within the drying space of said closed chamber, said means including a heating device within the drying space and distributed over the floor of the chamber 50 and spaced from a side wall of the chamber to cause a direct upward flow of air from the underlying floor area, and a cooling device within the drying space at the upright side of the chamber from which the heating coil 55 is spaced.

3. A drying room comprising a closed drying chamber devoid of partitions provided with heating means distributed over and disposed a short distance above the floor

of the chamber but in direct communication 60 with the floor area therebeneath so as to distribute the air directly upwardly through the chamber, and a cooling device positioned on a side wall of the chamber within the drying space with its cooling surface in direct 65 contact with the air of the drying space.

4. A drying room, comprising a closed drying chamber, a heating and distributing device extending across said chamber adjacent to the bottom thereof, consisting of a 70 series of steam pipes arranged in gradually decreasing spaced relation from one side of the chamber, and a cooling device located on one upright side of the chamber.

5. A drying room, comprising a closed 75 drying chamber, a heating and distributing device extending across the chamber a short distance above the bottom thereof, said device consisting of a series of steam pipes arranged in gradually decreasing spaced relation 80 from one side of the chamber, and a cooling device located within the chamber on the side wall thereof from which the spacing of the heating pipes decreases.

6. A drying room, comprising a closed 85 drying chamber having a cooling device located on one side thereof within the drying space of the chamber, and a heating and distributing device extending across said chamber a short distance above the floor thereof, 90 said device being spaced from the wall on which the cooling device is located and consisting of a series of pipes extending longitudinally of the chamber and arranged in gradually decreasing spaced relation from 95 the cooling side of the chamber.

7. A drying room, comprising a closed 100 drying chamber, a cooling device located on opposite side walls thereof adjacent to the top of the room, a heating and distributing device spaced from the walls on which the cooling device is located and extending across the chamber a short distance above the floor thereof, said device comprising a series of connected steam pipes extending longitudinally of the room and arranged in gradually decreasing spaced relation from 105 the sides toward the center of the room.

8. A drying room comprising a drying 110 chamber, and an air heating and distributing device comprising a series of pipes arranged in decreasing spaced relation transversely of the room beneath the material to be dried.
